UNITED STATES PATENT OFFICE.

JOHN C. DUJAT, OF NEW YORK, N. Y.

MEDICINE-DROPPER.

SPECIFICATION forming part of Letters Patent No. 783,688, dated February 28, 1905.

Application filed May 2, 1904. Serial No. 205,934.

To all whom it may concern:

Be it known that I, JOHN C. DUJAT, a citizen of the United States, and a resident of New York, in the county of New York and State of New York, have invented certain new and useful Improvements in Medicine-Droppers, of which the following is a specification.

The present invention relates to a medicine-dropper, and has for its object to arrange a device to be applied to a medicine-bottle by means of which the liquid contained in the bottle will be allowed to flow in drops, and thus enable the patient to take the right number of drops. The arrangement of this device is such that it can be readily attached to bottles with necks of different sizes.

The device consists of a conical funnel of any suitable material, preferably of glass. The top and the bottom of the funnel are open, the hole of the bottom being sufficiently narrow to permit the liquid to flow in drops. At its back the funnel is provided with a lateral projection serving to bear a spring-clasp, which may be made of suitable spring material and adapted to engage the neck of a medicine-bottle. The device is to be applied to the bottle crosswise to the longitudinal dimension of the latter, so that when the bottle is tilted over to pour out the liquid the funnel will extend downward and the liquid flowing into the funnel will flow out from the funnel in drops.

The present invention also relates to some other means, which will be hereinafter more particularly specified.

In order to make my invention more clear, the same is illustrated in the accompanying drawings, in which similar reference-numerals denote similar parts, and in which—

Figure 1 is a vertical section of the device, the latter being shown in use and as applied to a medicine-bottle; Fig. 2, a front view of the device; Fig. 3, a top view thereof; Fig. 4, a vertical section through a modification of the device; Fig. 5, a front and Fig. 6 a top view thereof.

Referring to the drawings, the numeral 1 indicates a medicine-bottle; 2, its neck.

The device forming the subject of the present invention consists of a conical funnel 4, made of any suitable material, preferably of

glass, this latter material being antiseptic. As seen from the drawings, the funnel has an open top and bottom, the hole 6 of the bottom being sufficiently narrow as to cause the liquid to flow out in drops. At its back the 55 funnel 4 is provided with a lateral projection 5, serving as a bearing for a clasp 3, which may be made of a strip of resilient material, as metal, hard rubber, or the like, and is attached to the projection 5 by simply bending 60 this strip around the latter. To prevent the turning of the clasp 3 upon the projection 5, the latter may be made oblong, as shown, or square. At one side of the funnel a spout 7 may be provided to allow the surplus liquid 65 to be poured back into the bottle. To prevent a lateral displacement of the clasp 3 upon the projection 5, the free end of the latter may be provided with a flange securing the clasp 3 in position.

In order to apply the device to a medicine-bottle, the neck of the bottle is placed between the two ends of the clasp and the latter is pressed upward, whereby the spring-arms of the clasp will be opened and engage the neck 75 2 of the bottle 1, as shown in the drawings.

A scale denoting the number of drops contained in the funnel at a particular part thereof may be provided on the outer surface of the glass funnel, whereby the patient will be enabled to always control the number of drops to be taken.

In Figs. 4, 5, and 6 a modification of the above-described arrangement is shown. In this modification the spout does not extend 85 outward as in the first arrangement, but a spout 9 is arranged inside the funnel 4, so as to project into the mouth of the bottle when the funnel is applied to the latter. This spout may be at its inner end wider than at its outer 90 end in order to permit the liquid to be easier poured back into the bottle when the latter is turned upright.

It will be seen that when the funnel is applied to the bottle and the latter tilted over 95 into the position shown the liquid contained in the bottle will flow into the funnel through and around the spout, while when the bottle is turned upright again the liquid will flow back into the bottle through the spout 9. I 100

do not confine myself, however, to the particular arrangement shown, as it will be understood that various changes of the different parts may be made without departing from 5 the spirit of my invention.

What I desire to secure by Letters Patent is—

1. A medicine-dropper, comprising a conical funnel of any suitable material, preferably 10 of glass, said funnel being provided with an open top and bottom, the hole of the bottom being sufficiently narrow to cause the liquid to flow out in drops, a lateral projection at the 15 back of the funnel, a clasp borne upon said projection and adapted to engage the neck of the medicine-bottle in such a manner that when the bottle is tilted over the funnel will extend downwardly crosswise to the longitudinal dimension of the bottle and permit the liquid to 20 flow into the funnel, substantially and for the purpose as specified.

2. A medicine-dropper, comprising a conical funnel of any suitable material, preferably 25 of glass, said funnel having an open top and bottom, the hole of the bottom being sufficiently narrow to cause the liquid to flow in drops, a lateral projection at the back of the funnel, a clasp borne upon said projection and adapted to engage the neck of the medicine-bottle, a scale on the outer surface of the funnel, a spout inside the funnel, said spout projecting outward and being curved so as to project into the neck of the bottle when in use, 30 substantially and for the purpose as specified.

Signed at New York, in the county of New 35 York and State of New York, this 30th day of April, 1904.

JOHN C. DUJAT.
